CONTROL SYSTEM

Walter Ernst, Mount Gilead, Ohio, assignor to
 The Hydraulic Development Corporation, Inc.,
 Wilmington, Del., a corporation of Delaware

Application March 11, 1942, Serial No. 434,270

10 Claims. (Cl. 303—6)

This invention relates to control systems and, in particular, to control systems for hydraulic presses such as die casting machines.

In hydraulic press systems, such as used in connection with die casting, one hydraulic circuit is usually provided for closing the molds and a second hydraulic circuit brings about the actual injecting operation.

With such systems it may happen that, for some reason, for instance due to leakage, a break in the control system, or an error on the part of the operator, the second hydraulic circuit is put into action for bringing about an injecting operation, while the molds are not completely closed. In this instance, the material would be injected into the open molds and not only be wasted, but might even severely injure the operator as well as the machine.

Accordingly, it is an object of the present invention to provide a safeguard against such accidents.

It is another object of the invention to provide a control system for use in connection with hydraulic press systems comprising two circuits for subsequently actuating two separate members, in which operation of the second member is possible only when and as long as a predetermined pressure acts upon the said first member.

Another object of the invention consists in the provision of a hydraulic press system having two fluid operable members, in which the operation of one fluid operable member is automatically interrupted whenever the other fluid operable member fails to be acted upon by a predetermined pressure.

It is still another object of the invention to provide a hydraulic system having two fluid operable cylinder-piston-assemblies, in which the supply of pressure fluid to one of said cylinder-piston-assemblies is controlled by a valve which, in its turn, is automatically controlled so that it may be shifted into open position for conveying pressure fluid to said last mentioned cylinder-piston-assembly when a predetermined pressure has been established in the other cylinder-piston-assembly, whereas said valve is prevented from being shifted into said open position, or is automatically shifted into closing position when the pressure in said other cylinder-piston-assembly is below said predetermined pressure.

These and other objects and advantages of the invention will appear more clearly from the following specification in connection with the accompanying drawing.

General arrangement

The control system according to the invention which is illustrated in connection with a die casting machine having a clamping plunger for closing the molds and an injecting plunger for injecting the material into the molds, comprises a valve controlling the supply of pressure fluid to the injection cylinder.

According to the invention, a control plunger is provided which is hydraulically connected with the clamping plunger so that when the clamping plunger has performed its clamping stroke, the pressure acting upon said clamping plunger is conveyed to the control plunger and moves the latter into a first position against the thrust of a spring, thereby allowing said control valve to be shifted into a predetermined position enabling the supply of pressure fluid to said injecting plunger.

If for some reason the pressure acting on the control plunger drops or the pressure acting on the control plunger is beneath a predetermined pressure, the said spring moves said control plunger into a second position, thereby preventing said control valve from being moved into said predetermined position so that no fluid pressure can be conveyed to said injecting plunger.

Structural arrangement

Referring to the drawing in detail, the latter diagrammatically illustrates an injection press comprising a clamping cylinder 1 with a clamping ram 2 reciprocably mounted in said clamping cylinder 1. Connected to and movable by the clamping ram 2 is a mold half 3 for cooperation with a stationary mold half 4. Connected to the mold half 4 is an injection chamber 5 adapted to receive molding material which may be injected by an injection plunger 6 into the mold halves 3 and 4. The injection plunger 6 has a fluid operable portion reciprocably mounted in an injection cylinder 7.

One end of the injection cylinder 7 is connected by a conduit 8 with a four-way valve 9 of any standard design, in which a reciprocable valve member 10, when shifted into one position, establishes fluid connection between the conduit 8 and a conduit 11, while simultaneously connecting the conduit 12, leading from the injection cylinder 7 to the four-way valve 9, with an exhaust conduit 13. When the valve member 10 is shifted into another position, fluid connection is established between the conduits 8 and 13, while simultane-

ously fluid communication is established between the conduits 11 and 12.

The conduit 13 leads to a conduit 14 having one end connected to a fluid reservoir or surge tank 15, while the other end leads to a four-way valve 16. The four-way valve 16 may likewise be of any standard design and has a valve member 17 which, when moved into one position, establishes fluid connection between the conduit 14 and the conduit 18, while simultaneously establishing fluid connection between the conduit 19 and the conduit 20 leading to the conduit 11. The conduits 18 and 19 are respectively connected with the ends of the clamping cylinder 1. When the valve member 17 is shifted into the opposite position, the conduit 18 is connected with the conduit 20, while simultaneously fluid connection is established between the conduits 14 and 19.

The valve member 17 is pivotally connected by a link 21 with a three-arm lever 22, having foot pedals 23 and 24 for selectively shifting the lever 22 into clockwise or anticlockwise direction. Similarly, the valve member 10 is connected by a link 25 with a three-arm lever, generally designated 26, having foot pedals 27 and 28 for shifting the valve member 10 in one or the other direction.

The valve member 10 has an extension 29 passing through a control cylinder 30 and adapted to be engaged by a control piston 31 reciprocably mounted in the control cylinder 30. Arranged between one side of the control piston 31 and the adjacent end of the control cylinder 30 is a strong spring 32 which urges the control piston 31 continuously into engagement with the extension 29 of the valve member 10.

The hydraulic system shown in the drawing is supplied with pressure fluid from a pressure fluid source or pump 33, the pressure side of which is connected to the conduit 11, while the suction side communicates through the conduit 34 with the surge valve 15.

Operation

It may be assumed that the mold halves 3 and 4 are in open position so that the clamping ram 2 and the injection plunger 6 are in retracted position, while the foot pedals 23 and 27 are in their lowermost position and the foot pedals 24 and 28 are in their uppermost position. In this instance, the extension 29 will be in its left hand position so that the spring 32 has moved the control piston 31 into and holds the same in its left hand position. The spring 32 is strong enough to prevent movement of the piston 31 by the extension 29 from its left hand position to the position shown in the drawing, in other words, when the piston 31 is held in its left hand position by the spring 32, the operator will not be able to depress the foot pedal 28.

In order to start a working cycle, the operator now depresses the foot pedal 24, thereby moving the valve member 17 into its right hand position. This establishes fluid connection between the conduits 20 and 19, while simultaneously connecting the conduit 18 with the conduit 14. Consequently, pressure fluid from the pump 33 flows through conduits 11 and 20, valve 16 and conduit 19 into the clamping cylinder 1 and moves the clamping ram 2 toward the right, thereby bringing the mold half 3 into engagement with the stationary mold half 4 and closing the same. During this operation, fluid is exhausted from the clamping cylinder 1 through conduits 18 and 14 into the tank 15.

As soon as the mold halves 3 and 4 are closed so that further rightward movement of the ram 2 is not possible, pressure begins to build up in the conduit 19 which pressure is conveyed through conduit 35 into the left end of the control cylinder 30 where it acts upon the control piston 31 and, after having reached a predetermined value, overcomes the force of the spring 32, thereby moving the control piston 31 into the position shown in the drawing. When the piston 31 has reached this position, it will be possible for the operator to completely depress the foot pedal 28, thereby shifting the valve member 10 into its right hand position, in which the conduit 11 communicates with the conduit 8, while fluid connection is established between the conduits 12 and 13.

Consequently, pressure is now conveyed from the pump 33 through conduits 11 and 8 into the injection cylinder 7, which pressure advances the injection plunger 6 toward the left to eject material from the injection chamber 5 into the mold. During this operation, fluid is exhausted from the injection cylinder 7 through conduits 12 and 13 into the tank 15.

After the injecting operation has been completed, the operator depresses the foot pedals 23 and 27 to reverse the valves 9 and 16, thereby also reversing the movement of the clamping ram 2 and the injection plunger 6. This spaces the mold halves 3 and 4 from each other and allows removal of the work piece from the molds.

It may now be assumed that, during the first phase of the cycle, i. e., while the clamping ram 2 was moving toward the right, the operator thought that the mold halves 3 and 4 had already been closed and tried to depress the pedal 28. However, since at this time the piston 31 is still in its left hand position and held in the same by the spring 32, the extension 29 is positively prevented from being shifted toward the right, thereby positively preventing the operator from depressing the pedal 28 and starting a premature operation of the valve 9. If during the actual injection operation the pressure in the clamping cylinder 1 suddenly drops for some reason, for instance due to a break in the pipe system, the pressure in the left hand portion of the control cylinder 30 likewise drops and the strong spring 32 immediately shifts the piston 31 toward the left, thereby preventing further supply of pressure fluid to the injection plunger 6 and stopping the injecting operation of the latter.

As will be clear from the above, the invention constitutes a material safeguard against accidents caused by the advancement of the injection plunger 6 into the injection chamber 5 while the mold halves 3 and 4 are not properly closed or not under the desired clamping or closing pressure.

It should be noted that, while the invention has been described, for the sake of simplicity, in connection with two four-way valves operated by the operator, it is of course understood that these valves may also be operated subsequently in an automatic manner by means of any control systems of standard design. Furthermore, while the present invention has been described with one delivery pump only, it is of course understood that, if desired, separate pumps may be provided for supplying pressure fluid to the clamping and injection cylinder respectively. In this instance, the supply of one pump to the clamping cylinder will be con-

trolled by the four-way valve 16, while the supply of pressure fluid from the other pump will be controlled by the four-way valve 9. The operation of the control system, including the control piston 31 and cylinder 30, will obviously not be impeded by such a variation of the hydraulic system.

It is also to be understood that, although the invention has been described in connection with a die casting machine, it is by no means limited thereto and may be used in connection with any hydraulic system in which a plurality of fluid operable plungers are operated subsequently, and in which it is desired that pressure fluid should be conveyed to one plunger only after and as long as another plunger is acted upon by a predetermined fluid pressure.

It will be understood that I desire to comprehend within my invention such modifications as come within the scope of the claims and the invention.

Having thus fully described my invention, what I claim as new and desire to secure by Letters Patent, is:

1. In a hydraulic system, a first fluid operable plunger, a second fluid operable plunger, means for admitting pressure fluid to said first plunger, means for admitting pressure fluid to said second plunger, means for preventing the supply of pressure fluid to said second plunger prior to the establishment of a predetermined pressure on said first plunger, and means responsive to a drop in pressure on said first plunger below said predetermined pressure for automatically interrupting the supply of pressure fluid to said second plunger.

2. In a hydraulic system, a first fluid operable plunger, a second fluid operable plunger, first valve means for controlling the supply of pressure fluid to said first plunger, second valve means movable selectively from a first position in which it prevents supply of pressure fluid to said second plunger into a second position for admitting pressure to said second plunger, and control means normally preventing movement of said second valve means into said predetermined position, said control means being arranged to move into inoperative position in response to a predetermined pressure on said first plunger, to thereby allow movement of said second valve means into said predetermined position, and also being arranged to bring about a return of said second valve means into its first position in response to a drop in pressure on said second plunger below said predetermined pressure.

3. In a hydraulic system, a first fluid operable plunger, a second fluid operable plunger, first valve means for controlling the supply of pressure fluid to said first plunger, second valve means movable from its closing position into its open position for admitting pressure fluid to said second plunger, a control member movable into a first position for preventing movement of said second valve means into said predetermined position and movable into a second position to allow movement of said second valve means into said second position, yielding means continuously urging said control member into said first position, and conduit means hydraulically connecting said first plunger with said control member for conveying pressure to the latter for moving the same into said second position in response to a predetermined pressure on said first plunger, said yielding means being

adapted in response to a drop in pressure in said conduit means below said predetermined pressure to automatically cause said control member to return said second valve means into its closing position.

4. In a hydraulic system, a first cylinder, a first plunger reciprocable in said first cylinder, a second cylinder, a second plunger reciprocable in said second cylinder, valve means operable to subsequently admit pressure fluid to said first cylinder and said second cylinder, and means responsive to a predetermined pressure condition in said first cylinder for automatically actuating said valve means so as to prevent further supply of pressure fluid to said second cylinder.

5. In a hydraulic system, a first cylinder, a first fluid operable plunger reciprocable in said first cylinder, a second cylinder, a second fluid operable plunger reciprocable in said second cylinder, first valve means for controlling the supply of pressure fluid to said first cylinder, second valve means for controlling the supply of pressure fluid to said second cylinder, and control means hydraulically connected with said first cylinder for actuating said second valve means to interrupt the supply of pressure fluid to said second cylinder in response to a decrease in pressure in said first cylinder beyond a predetermined value.

6. In a hydraulic system, a first cylinder, a first fluid operable plunger reciprocable in said first cylinder, a second cylinder, a second fluid operable plunger reciprocable in said second cylinder, first valve means for controlling the supply of pressure fluid to said first cylinder to actuate said first plunger, second valve means controlling the supply of pressure fluid to said second cylinder, a control cylinder hydraulically connected with said first cylinder, and a fluid operable control plunger reciprocable in said control cylinder and normally preventing movement of said second valve means into position for admitting pressure fluid to said second cylinder, said control plunger being arranged for movement into inoperative position in response to a predetermined pressure in said first cylinder.

7. In a hydraulic system, a first fluid operable plunger, first valve means movable into position for conveying pressure fluid to said first plunger, a second fluid operable plunger, second valve means movable into a predetermined position for admitting pressure fluid to said second plunger, yielding means normally preventing movement of said second valve means into said predetermined position, and means responsive to a predetermined pressure on said first plunger for making said yielding means ineffective to thereby allow movement of said second valve means into said predetermined position.

8. In a hydraulic system, a first fluid operable plunger, first valve means operable to admit pressure fluid to said first plunger, a second fluid operable plunger, second valve means including a reciprocable valve member movable into a predetermined position for admitting pressure fluid to said second plunger, a reciprocable control plunger normally urged into a first position for preventing said valve member from being moved into said predetermined position, and means responsive to a predetermined pressure on said first plunger for moving said control plunger into a second position to allow

movement of said valve member into said predetermined position.

9. In a hydraulic system, a first fluid operable plunger, first valve means for controlling the supply of pressure fluid to said first plunger for actuating the same, a second fluid operable plunger, second valve means including a reciprocable valve member movable selectively into a predetermined first position for admitting pressure fluid to said second plunger or into a predetermined second position for preventing the supply of pressure fluid to said second plunger, a control cylinder hydraulically connected with said first plunger, and means associated with said control cylinder for continuously urging said valve member into said predetermined second position, said means being movable into inoperative position in response to a predetermined pressure on said first plunger while

maintaining its tendency to urge said second valve means into said second predetermined position.

10. In a hydraulic system, a plurality of fluid operable plungers, a plurality of control valves respectively associated with said plungers for admitting pressure fluid thereto to actuate said plungers, and means preventing the movement of one valve into position for admitting pressure fluid to the plunger pertaining thereto prior to the establishment of a predetermined pressure on the plunger previously actuated, said means also being operable automatically to interrupt the supply of pressure fluid to said first mentioned plunger when the pressure on said last mentioned plunger drops below a predetermined value.

WALTER ERNST.
